UNITED STATES PATENT OFFICE.

HOWARD ECKEL, OF LOS ANGELES, CALIFORNIA.

PUMPING MECHANISM FOR VACUUM-CLEANERS.

1,138,464.

Specification of Letters Patent.

Patented May 4, 1915.

Application filed May 16, 1914. Serial No. 839,011.

To all whom it may concern:

Be it known that I, HOWARD ECKEL, a citizen of the United States, residing at Los Angeles, in the county of Los Angeles and State of California, have invented certain new and useful Improvements in Pumping Mechanism for Vacuum-Cleaners, of which the following is a specification.

My invention relates to vacuum cleaners of the type employing a casing and one or more bellows, together with a dirt receptacle, the purpose of my invention being to produce a neat and compact vacuum cleaner having a minimum of parts, and all of its parts being readily accessible.

My invention further relates to improved mechanism for actuating the vacuum bellows by hand, in such manner that practically any relative movement between the handles employed will cause the device to produce a partial vacuum within the casing.

My invention further relates to various improvements in vacuum cleaners, for the purpose of improving the general efficiency thereof.

Reference is made to the accompanying drawings forming a part of this specification, and in which like letters indicate like parts.

Figure 1 is a perspective of my improved vacuum cleaner complete. Fig. 2 is a fragmentary perspective partly broken away to show the interior of the casing and the dirt receptacle. Fig. 3 is a fragmentary view partly in plan and partly in section, showing the link connections for the bellows. Fig. 4 is a detail view, showing in section the tongue and parts immediately associated therewith for enabling the operator to handle the device. Fig. 5 is a section, substantially on the line 5-5 of Fig. 6, looking in the direction of the arrow, and showing the valve mechanism. Fig. 6 is a vertical section, on the line 6-6 of Fig. 5, looking in the direction of the arrow, and showing the bellows mechanism with its valves.

A dirt receptacle is shown at 7, and has generally the form of a flat box. The nozzle appears at 8, and at 9 is a bail for detachably holding the nozzle upon the dirt receptacle. Mounted upon the nozzle 8 is a lug 9^a which is engaged by the bail 9 in order to secure the nozzle upon the dirt receptacle. The bail 9 is journaled upon a pair of ears, one of which is shown at 10, and is adapted to swing upwardly, when disconnected by

hand from the lug 9^a. A dirt bag is shown at 11, and is located within the dirt receptacle 7 and in communication with the nozzle 8.

Casters 12, provided with caster wheels 13, are mounted upon a casing 14, the latter having substantially the form of a keystone, and being provided with gauze windows 15 for discharging air. Located centrally within the casing 14 is a partition 16, this partition being provided with a slot 17 registering with an opening 17^a in the bottom of the casing communicating with the dirt box or receiver, as may be understood more particularly from Figs. 2, 5 and 6. Mounted rigidly upon opposite sides of the partition 16 are bellows plates 18, 19, the latter being provided with valve holes 20, 21. Extending over these holes are valves 22, 23. Two other bellows plates are shown at 24, 25. These two bellows plates are movable relatively to the partition 16 and bellows plates 18 and 19, and are provided with valve holes 26, 27 and with valves 28, 29. Bellows webs 30 are shown at 30, 31 and are connected with the bellows plates 18, 24, 19, 25.

Mounted upon the bellows plates 24, 25 are brackets 32, 33, which extend through slots 14^a in the casing 14. Two links 34, 35 are pivotally connected with the brackets 33, 32. A clevis 36 is mounted upon the partition 16 and is provided with a bolt 37. A tongue is shown at 38 and is provided with a slot 39 extending through it. A hand lever 41 extends through the slot 39, and is connected with the tongue 38 by a pivot bolt 42. The tongue 38 is provided with a metallic head 40, the latter having a slot 40^a extending horizontally through it, and an opening for the bolt 27. The hand lever 41 is provided with a portion 43 extending through this slot. The links 34, 35 are pivotally connected to the portion 43 of the hand lever. The parts are so arranged that whenever the hand lever 41 is moved upon the pivot bolt 42, relatively to the tongue 38, both of the bellows plates 24, 25 are shifted relatively to the partition 16.

The various bellows plates and parts associated therewith together constitute two distinct bellows so arranged that a single movement of the hand lever 41 and tongue 38 relatively to each other will cause one of the bellows to be inflated and the other to be deflated. The tongue 38 is provided with a handle 44, and the hand lever is provided

with a handle 45, to facilitate the control of these parts by hand. Rivets 46, (see Fig. 4) secure the tongue 38 and the head 40 together.

5. The operation of my device is as follows: The parts being assembled and arranged as shown and described, the operator grasps the handles 44, 45, and pushes or pulls the device along over the floor or other surface 10 to be cleaned. The caster wheels 13 facilitate the handling of the device as a whole, and enable the operator to bring the nozzle 8 quickly over any part which is to be operated upon by the cleaner. As the device 15 is thus moved bodily around, or even while it remains stationary, the operator, by moving the handles 44 and 45 relatively to each other, operates the two bellows within the casing. Air, containing dirt removed 20 from the article to be cleaned, is carried into the dirt receptacle 7, and the dirt is retained in the dirt bag 11. The air passes upwardly through the slot 17 and out through the various valve holes and makes its escape 25 through the windows 15.

I do not limit myself to the precise construction shown, and variations may be made therein without departing from the spirit of my invention.

- 30 Having thus described my invention, what I claim as new and desire to secure by Letters Patent is as follows:

1. In a vacuum cleaner, the combination of a receiver, a casing connected with said receiver and having substantially the form of a keystone, a portion of said casing being wider than said receiver, casters mounted upon the edges of the portion thus wider than said receiver, a tongue connected with 35 said casing, bellows mounted within said casing, and means operable by hand for actuating said bellows.

2. In a vacuum cleaner, the combination of a receiver, a casing secured to said receiver, a tongue pivotally connected with said casing, a hand lever pivotally connected with said tongue, bellows mechanism located within said casing, and links connected with said bellows mechanism and with said hand lever.

3. In a vacuum cleaner, the combination of a receiver, a casing connected therewith, a partition mounted within said casing and provided with a slot which communicates

with said receiver, a plurality of bellows 55 mounted within said casing, separate links connected with the different bellows, a single hand lever connected with all of said links and adapted to swing relatively to said casing, and a tongue pivotally connected 60 with said casing and adapted to swing relatively to the same, said tongue being pivotally connected with said hand lever.

4. In a vacuum cleaner, the combination of a receiver, a casing connected therewith, 65 a partition located within said casing and provided with an opening which communicates with said receiver, two bellows located within said casing, one disposed on each side of said partition and communicating 70 with said opening therein, separate links connected with the different bellows, a hand lever connected with all of said links, a tongue connected with said casing, and a pivot pin extending through said tongue 75 and through said hand lever for enabling relative movements of said tongue and said hand lever to actuate all of said bellows.

5. In a vacuum cleaner, the combination of a casing, a tongue pivotally connected 80 therewith and adapted to swing relatively thereto, a plurality of bellows mounted within said casing, links pivotally connected with said bellows, and a hand lever connected with said links, said hand lever being pivotally connected with said tongue, and free 85 to swing bodily therewith relatively to said casing.

6. In a vacuum cleaner, the combination of a casing, a tongue pivotally connected 90 therewith and adapted to swing relatively thereto, a plurality of bellows mounted within said casing, links pivotally connected with said bellows, a hand lever pivotally connected with said links, the said hand lever being 95 pivotally connected with the tongue and free to swing bodily therewith relatively to said casing, the hand lever and tongue being each provided with a handle, and casters for supporting said casing.

In testimony whereof I have signed my name to this specification in the presence of two subscribing witnesses.

HOWARD ECKEL.
